ABRADING APPARATUS

Robert B. Huyett, Hagerstown, Md., assignor to
 Pangborn Corporation, Hagerstown, Md., a corporation of Maryland

Application July 19, 1937, Serial No. 154,485

17 Claims. (Cl. 51—9)

The present invention relates to abrading apparatus of the general character wherein castings or other articles are subjected to the action of an abrasive blast and cleaned of adhering moulding sand, scale and the like, and it is particularly concerned with apparatus wherein a high speed throwing wheel is employed to project the blast stream against the work.

By reason of the relative massiveness of throwing wheels and their necessary adjuncts it has been the practice to bring the work to the blasting apparatus and manipulate it in the blast stream to expose all of its surfaces and clean the entire article. With heavier articles which do not lend themselves readily to manipulation in the blast stream it has been the practice heretofore to mount the article on a truck, push it into a blast room and clean it with an air blast nozzle. The article is then turned over to clean the underside thereof.

The invention aims to provide an apparatus utilizing one or more blast wheels, together with means conveying relatively massive articles of work to the apparatus and mechanism for causing the blast wheels to traverse the article and efficiently clean all of the exposed surfaces thereof, thereby doing away with hand labor and air blast nozzles.

Another object it is to provide a machine for cleaning relatively heavy articles of work which will cause at least one blast stream to progressively move along the work and clean a path therealong, and having means for causing said blast stream to clean another path adjacent the first path, and the machine being operable to repeat the cycle until the article of work is entirely cleaned.

Another important object is to provide an abrading apparatus embodying one or more blast wheels mounted on a carriage for causing blast streams to traverse the work and having means for varying the speed at which the streams traverse the work, whereby a part or parts of the work can be subjected to a more prolonged and hence more intense cleaning action than other parts.

A further object is to provide a travelling carriage having blasting apparatus thereon and adapted to travel in a predetermined direction, together with a work support and a work pushing mechanism mounted for movement in a direction substantially normal to the direction of travel of the carriage and operable to propel the work one or more steps at a time over the work support to subject a fresh area thereof to the

action of the blast as the carriage travels back and forth in its path.

Another object is to provide an apparatus embodying a work support and having a carriage mounted for movement in a substantially horizontal plane above the support and having one or more blast devices for directing a stream of abrasive at an inclination to the plane of travel of the carriage whereby the sides as well as the top of the work are subjected to an abrading action.

It is a further object to devise an abrading apparatus embodying a work support, a travelling carriage above the work support and adapted to travel in a path along the work to be cleaned and direct at least one blast stream thereupon, and a pusher operable to automatically move the work a predetermined distance in a direction substantially normal to the path of said carriage each time or plurality of times the carriage moves throughout its range of travel.

A further object is to provide an abrading apparatus having a travelling carriage upon which abrasive projecting means are mounted and having means for conveying abrasive from a stationary abrasive supply to said carriage.

Further objects of the invention will become apparent as the specification proceeds in connection with the annexed drawings, and from the appended claims.

30 In the drawings:

Figure 1 is a side elevational view of a machine embodying the invention and parts thereof have been broken away to more clearly illustrate the structure involved.

35 Figure 2 is a front elevational view of the machine illustrated in Figure 1 and parts thereof have also been broken away to more clearly illustrate the structure.

Figure 3 is a fragmental front elevational view 40 of the machine of Figure 2, and illustrates the upper part of the machine that is not shown in Figure 2.

Figure 4 is a fragmental side elevational view of the upper portion of the machine of Figure 1 45 and illustrates the structure not shown in that figure.

Figure 5 is an enlarged side elevational view of the automatic valve for controlling the abrasive flow.

50 Figure 6 is a diagrammatic top plan view of the machine and illustrates schematically the various switches for controlling the different motors of the apparatus.

Figure 6A is a top plan view on an enlarged scale of the stop cams shown in Figure 6.

Figure 7 is a diagrammatic illustration of the preferred form of centrifugal wheel that is used in the machine.

Figure 8 is a diagrammatic front view of the blast wheels of the machine and illustrates the manner in which the blast streams impinge the work.

Figure 9 is a diagrammatic view of the wheels shown in Figure 8, but shows a side view of the wheels.

Figure 10 is a view similar to Figure 9, but illustrates the action of the blast stream when the wheels are rotated in directions opposite to that of Figure 9.

With continued reference to the drawings, wherein like reference characters have been employed to designate like parts throughout the several views thereof, broadly the device comprises a table A upon which the work is placed, which is mounted for rotation about a vertical axis to bring the work into a cabinet B; a carriage C upon which a pair of blast wheels D₁ and D₂ are mounted, the carriage being mounted for movement in a horizontal plane to allow the blast streams to progressively impinge upon the work from one end to the other thereof.

Abrasive is fed to the wheels by distributing mechanism designated generally as E and an abrasive recovering and purifying apparatus designated as F is employed to pick up the spent abrasive, purify it and return it to the blast wheels. As the wheels are reciprocated back and forth over the work contained in cabinet B, a pusher designated as G is employed to periodically slide the work over the table surface in a direction substantially normal to the direction of carriage travel for presenting a fresh area of the work to the action of the blast streams.

Work table and cabinet

Referring to Figures 1 and 2, cabinet B is provided with a top wall 10 having an elongated opening 11 therein through which the blast streams are projected. The cabinet is also provided with side walls and a rear wall 12, the front of the cabinet being open to permit the work to be carried into and out of the housing.

Table A is journaled for rotation about a substantially vertical axis on a pedestal 13 and is made up of a pair of long girders 14 which each carry longitudinal work supporting rails 15. A pair of cross beams 16 bridge girders 14 and connect the latter to a hub structure 17 which is journaled on pedestal 13. Table A is also provided with an upwardly extending central structure 18 which terminates in a shaft portion 19 which in turn is journaled in the bearing 21. Bearing 21 is carried by a pair of cross members 22 which in turn are supported by a pair of longitudinal beams 23 and 24 which extend across the front of the machine and are supported in any suitable manner.

Work may accordingly be placed upon rails 15 in the front of the machine and the table rotated a half revolution to carry the work into the interior of the cabinet B.

In Figure 6 there is diagrammatically illustrated one form of means for rotating table A which may, if desired, be manually rotated. In this figure there is illustrated a motor 20 having a sprocket 20' which meshes with an endless driving chain 20" passing around table A. The circuit for motor 20 is preferably controlled in a manner that will be hereinafter set forth.

A third beam 25 also extends across the rear of

the machine which supports one of the tracks for carriage C, and the latter will now be described.

Blast wheel carriage

Carriage C is provided with four wheels 26 which ride upon a pair of rails 27 and 28 supported upon beams 24 and 25, respectively. Carriage C is made up of side plates 29 and 31 which are interconnected by a pair of bed plates 32 and 33 which support the abrasive throwing wheels. The upper edges of side plates 29 and 31 are bridged by a pair of beams 34 and 35 which in turn support a pair of further beams 36 and 37.

Abrasive wheels D₁ and D₂ are of the identical construction and hence only one of them will be described and similar reference characters will be applied to both of them. Each wheel is provided with a base 40 which is secured to its respective bed plate 32 and 33. The wheel proper is designated as 41 and is seen diagrammatically in Figure 7. Wheel or rotor 41 carries a plurality of blades 42 which terminate short of the center of rotation to provide a central space in which a feed chamber 43, having a discharge opening 44, is disposed. Mounted for rotation with rotor 41 is a bladed impeller 45 having a hollow center into which the abrasive is introduced. Cage 43 is mounted for angular adjustment whereby the discharge stream from the wheel may be placed in any desired direction.

Rotor 41 is mounted upon a shaft 47 which is journaled on base 40 and is provided with a sheave 48. An electric motor 49 is also mounted upon base 40 and is provided with a driving sheave 51 which is connected to sheave 47 by a plurality of V-belts 52 known as "Texrope" drive. The wheel is enclosed by a housing 53 and extending through an opening in the housing is an abrasive supply pipe 55 which extends into cage 43 and communicates with the interior of impeller 45.

Suitable openings are provided in bases 32 and 33 to allow the wheels to project therethrough, and the bottom of carriage C is likewise open so that the abrasive streams issuing therefrom may freely pass downwardly upon the work supported upon table A.

Although a four-bladed wheel is shown it is to be understood that if desired a wheel having more or less than four blades may be used or in fact any other suitable type of apparatus that will impart an abrading velocity to the abrasive.

Carriage C may be reciprocated by any suitable means but I preferably employ a motor 56 which is connected to the input side of a gear box 57 having an output sprocket 58. A chain 59 passes over sprocket 58 and meshes with a larger sprocket 61 mounted on a shaft 62 journaled on beam 23. A drum 64 is secured to shaft 62 and a cable 65 is secured thereto and makes a plurality of turns therearound. One end of cable 65 is connected to one end of carriage C at 66 and the other end passes over a pulley (not shown) and is connected to the other end of carriage C at 67. It is accordingly apparent that rotation of shaft 62 in a clockwise direction will cause carriage C to move to the right in Figure 2, and counterclockwise rotation will cause the carriage to move to the left.

Abrasive feeding mechanism

Abrasive is supplied to the wheels D₁ and D₂ as follows. A trough-shaped structure 69 is

mounted above the wheel on carriage C, and is supported at its front end by a plate 71 connected to beam 37, and at its rear end it is connected to beam 36 by means of a plate 72. The mid-portion of the structure is connected to side plate 31 by means of an upright 73.

A screw conveyor 75 is disposed in trough 69 and extends through either end thereof, and is journaled in bearings 76 and 77 located exteriorly of trough 69. Mounted on the screw conveyor is a sprocket 79 which carries a chain 81 meshing with a sprocket 82 carried by the output shaft of a speed reducer 83. Speed reducer 83 is driven by motor 84 and the two units are supported on carriage C by means of a pair of plates 85 which provide a bed having a bottom 86.

Communicating with the interior of trough 69 are abrasive delivery spouts 87, 88 and 89. Spout 87 is connected to the feed pipe 55 of wheel D₂, whereas spout 88 is connected to feed pipe 55 of wheel D₁. Spout 89 is known as an overflow spout or by-pass and communicates with a pipe 91 which is operable to return the abrasive to the abrasive recovery system to be hereinafter described.

Operation of motor 84 causes feed screw 75 to rotate and advance the abrasive from right to left in Figure 1 toward feed spouts 87, 88 and 89. A predetermined amount of abrasive is taken by feed spouts 87 and 88 and any excessive abrasive spills into the overflow or by-pass spout 89 and is returned to the abrasive recovery system.

Abrasive is introduced into trough 69 by means of a hopper 92 which communicates with an opening 93 in the upper side of trough 69. The hopper is supported on the carriage by means of a pair of uprights 94 and 95 and a cross piece 96. These elements are supported upon beam 36, and they are braced by means of a pair of brace rods 97.

As seen in Figure 1, hopper 92 is comparatively thin and is provided with an enlarged upwardly facing mouth 98 into which a feed spout 99 projects. In Figure 2, hopper 92 is seen to have an elongated upper edge whereby feed spout 99 may communicate therewith regardless of the reciprocated position of carriage C. Trough 69 is accordingly continuously supplied with abrasive during the reciprocation of the carriage C, and in view of the comparatively small volumetric capacity of hopper 92, it does not accumulate much abrasive at any time. As a matter of fact, it functions more in the nature of a pipe as it immediately conducts abrasive from spout 99 to the interior of trough 69. Any suitable means may be employed to conduct electricity to motors 49 and 84 located on carriage C, as for instance, a trolley wire assembly, or a flexible cable having sufficient slack in it to permit the carriage to move from one end of its travel to the other.

With reference to Figure 5, spout 99 communicates with a supply hopper 101 to which the abrasive is returned from the abrasive recovering and cleaning system.

A pair of abrasive control valves 102 and 103 are mounted upon a common shaft 104 which is journaled in spout 99. A crank arm 105 is mounted on shaft 104 exteriorly of spout 99 and is provided with an elongated slot 106. A control lever 107 is journaled on a pin 108 carried by a support 109 and carries a pin 111 which engages slot 106. The other end of lever 107 is pivotally connected at 112 to a link 113. The upper end of link 113 constitutes the armature of a solenoid 114 which is preferably connected in

the circuit with motor 84. The lower end of link 113 carries a counterweight 115.

As shown in Figure 5, solenoid 114 is energized thereby holding link 113 in its raised position, 5 which, through pin 111 and crank 105 holds abrasive valves 102 and 103 in the open position shown in Figure 5, thereby allowing abrasive to pass from hopper 101 through spout 99 to hopper 92. When the circuit is broken in response to shutting down motor 84, solenoid 114 is de-energized, thereby allowing counter-weight 115 10 to rock lever 107 counterclockwise and act upon the walls of slots 106 to rock crank 105 and close the abrasive valves. The abrasive flow to hopper 92 and trough 69 is accordingly automatically 15 cut off every time the screw conveyor motor is stopped. In this way the feed of the abrasive to the wheel is quickly stopped as spouts 88 and 87 are comparatively short and do not hold much residual abrasive. Stopping feed screw 75 promptly is advantageous because in that way trough 69 is maintained practically full of abrasive so that when motor 84 is again started and valves 102 and 103 are opened, a normal feed of 20 abrasive to the wheels is almost immediately re-established.

Abrasive recovery system

The bottom of housing B, as well as the upper 30 surface of table A are preferably perforated so that the spent abrasive may freely gravitate downwardly into a hopper below the floor level (not shown). This hopper is provided in well known manner with a screw conveyor for conveying the abrasive to one end of the hopper and into the boot of an elevator 117 which projects below the floor level. Elevator 117 (Figures 2 and 3) comprise a plurality of buckets 118 mounted upon a belt 119. Belt 119 passes over 35 a drive pulley 121 in the upper end of the elevator housing and a similar idler pulley in the bottom of the housing. The drive pulley is driven by a sprocket 123, a chain 124, and a sprocket 125. Sprocket 125 is in turn driven by 40 a motor 127 having a sprocket 128, meshing with a chain 129 which also meshes with a sprocket 131 and with a shaft on which sprocket 125 is mounted.

Buckets 118 discharge into a chute 133, which 45 in turn discharges into a rotatable drum 134.

Cylinder F constitutes a part of the abrasive 50 cleaning mechanism designated at 135 and it is rotated by means of a motor 136 operating through a shaft 137; a speed reducer 138; a sprocket 139; a chain 141; and a sprocket 142 mounted on a shaft 143 connected to the cylinder.

The abrasive cleaning mechanism may be of 55 any suitable type and it operates to remove molding sand, nails and other extraneous material from the abrasives before it is finally delivered to the clean abrasive supply hopper 101, the nails and other extraneous material being delivered to a chute 145 and then conducted to a waste receptacle 146. The molding sand is discharged 60 into a separate conduit 148 and then conducted to a suitable receptacle 149. A suction connection 147 is provided to carry away fine dust, etc.

Work pusher mechanism

After the blast mechanism has made one or 70 more passes over the work, pusher G is operated to advance it a predetermined distance before the work blast stream again traverses it in 75 order to present a fresh area to be cleaned.

Although the work pusher may assume various forms, in the present instance it is shown as made up of a bar 152, which is guided for movement in a horizontal plane by a plurality of rollers 153, which are rigidly journaled on any suitable elements of the apparatus. Bar 152 is reciprocated by means of a motor 154 which is mounted on a frame part 150. Motor 154 drives a speed reducer 155 which is provided with a sprocket 156. A pinion 157 is journaled below the bar and meshes with a toothed rack 158 secured to bar 152. A sprocket 159 is mounted on the shaft carrying pinion 157 and a chain interconnects it with drive sprocket 156. Accordingly, by controlling the circuit of motor 154, bar 152 may be advanced into or retracted from housing B. Bar 152 is provided with a head 160 of suitable form for engaging the work.

Operation

Assuming that the circuit for motors 49, 56, 84 and 20 are open, the operator places an article of work upon the pair of rails 15 on the portion of the table that extends outside the cabinet. The work may be of any desired character or form, providing it is not too large to enter the opening in the cabinet. The circuit for table motor 20 is then closed to cause table A to rotate through 180 degrees and which brings the article of work into the cabinet. The article of work is preferably placed near the periphery of the table, so that when it is moved into the cabinet it assumes a position corresponding substantially to the position W₁ shown in Figure 1.

The circuits for motors 127 and 136 are closed and then the circuits for motors 49, 56 and 84 are closed which causes the following events to take place:

- (1) Abrasive wheels D₁ and D₂ are started and brought up to speed very quickly.
- (2) Motor 84 drives screw 75 which starts feeding abrasive to the wheels.
- (3) Solenoid 114 lifts lever 107 and opens the abrasive valves 102 and 103, which start the abrasive flowing into hopper 92.
- (4) Motor 56 starts carriage C to moving toward one end of its direction of travel.

An interlock is preferably provided so that the various motors can not be started until table A reaches a predetermined stop position. The circuit also is designed to prevent the table motor 20 from operating until pusher rod 152 is disposed in its full line retracted position shown in Figure 1.

With the machine operating as just described, the carriage makes one pass over the work and cleans a part of the top surface or "swath" of the work piece, and also the side designated as 171. The manner in which the abrasive streams cooperate with each other to clean the work piece is shown in Figures 8 and 9. Referring to Figure 8, wheels D₁ and D₂ are inclined so that the blast streams issuing therefrom converge as shown in Figure 8, so that they almost meet at the surface of the work to be cleaned. Although they could be mounted so as to actually intersect before reaching the work piece a considerable loss of efficiency would occur because the particles from the two blast wheels would interfere with each other before striking the work.

In Figure 9 there is illustrated one manner in which streams may be adjusted through adjusting cages 43 of wheels D₁ and D₂. With reference to this figure, the streams issuing from wheels D₁ and D₂ are seen to overlap. Their spray an-

gles X are equal and the angle Y indicated is the area of overlap. In this figure the wheels are mounted so as to rotate toward each other, but if desired they may be mounted to rotate away from each other as shown in Figure 10. In that figure the spray angles X are the same as before, and the angle of overlap Y is very similar.

Assuming the apparatus is operating as just described, and the carriage has made one passage over the work, when the carriage approaches the end of its travel, means are preferably provided for automatically starting motor 154 so as to advance rod 152 one step which causes head 160 of the pusher to engage the work and slide it upon rails 15 into a new position. The carriage is then automatically reversed and makes a passage over the work in the opposite direction.

The automatic advancing of the pusher each time the carriage makes one or more passes over the work is continued until the work attains the position indicated as W₂ in Figure 1. When the work is in this position it is apparent that the blast streams are operable to clean the side surface of the work designated as 172. After the carriage has made its last passage with the work disposed in the position W₂, the motor 154 is reversed to retract rod 152 into the solid line position shown in Figure 1, and table A is then rotated to bring a fresh article of work into the blast chamber and simultaneously remove the cleaned article. It is of course understood that the fresh article will preferably have been placed on the other side of the table, while the first article is undergoing cleaning. During the work changing operation the other motors may or may not be stopped as desired, depending upon whether the succeeding article is to be immediately cleaned.

In view of the fact that elongated bodies of large size which this machine is particularly capable of handling, are often of non-uniform section throughout their length or for other reasons require that a more intensive cleaning action be imparted to one portion than another, there is preferably provided means for causing the carriage to move fast during a part of its travel and slower during another part of its travel. It is apparent that when the carriage moves at a normal fast rate the work will receive a normal cleaning action, whereas when it moves slowly the work will be more intensively cleaned. The positions at which the transitions from a fast to a slow speed or from a slow speed to a high speed occur can be adjusted to adapt the machine to any particular type of work. The mechanism is also adjusted so that this change in speed occurs entirely automatically.

In view of the fact that such electrical equipment as push button stop and start controls, reversing switches and interlocking electrical circuits are well known in the art, and as no novelty for them per se is claimed in the present application, the various electrical equipment is but diagrammatically illustrated in Figure 6.

With continued reference to this figure a simple push button switch 174 is employed to start motor 20. For stopping motor 20 there is shown a switch 175 embodying a pair of contacts 176 and 177 mounted on a plunger 178. Contact 176 controls the pusher motor and is operable to start the pusher when it is closed. Contact 177 is operable to open the circuits of the motor 20 and stop the table, and in order to render the operation automatic, contacts 176 and 177 are provided

with a plunger 178 which cooperates with a pair of fingers 179 and 181 provided on the table.

It is apparent that when the table arrives in the proper stopping position finger 179 or 181 will engage plunger 178 and open the table motor circuit by moving contact 177 to the right. It is also clear that as contacts 177 and 176 are interconnected the table and the pusher motor circuit can not be closed at the same time.

In order to make sure that the table will not be operated until pusher G has been retracted, a second interlocking safety switch 183 is provided and it embodies a pair of contacts 184 and 185 which are in series with the circuit of motor 20 so that the latter cannot be started until switch 183 is operated to close contacts 184 and 185.

In order to more clearly illustrate the operations involved, I have illustrated the pusher G as having a portion 186 upon which various parts of the electrical system are mounted. Mounted on the rear portion of member 186 is a cam 187 which cooperates with the operating rod 188 of switch 183. As seen in Figure 6, cam portion 187 of pusher G holds switch rod 188 in a position to close the circuit between contacts 184 and 185, and thereby make it possible to close the table motor circuit by operating push button 174. As cam 187 will only engage rod 188 when pusher G is in its rearmost position, it is apparent that the table motor circuit can not be closed until the pusher occupies this position. I have also illustrated a switch 189 which controls the wheel carriage motor 56 and solenoid 114 and motor 184. If desired, the circuit for motors 49 may also be controlled by this same switch.

Also mounted on member 186 is a stop switch 192 for motor 154 and it embodies a plunger 193 which cooperates with a plurality of stationary but adjustable supported cam members 194. Members 194 are adjustably mounted on a plate 195 by means of screws 194a. Plate 195 is in turn adjustably supported on any suitable part of the machine by a pair of screws 195a. The slots in plates 194 and 195 permit the plates to be adjusted lengthwise of the path of travel of the pusher so that they may actuate switch 193 in any desired manner. As the pusher is advanced and plunger 193 strikes the first cam 194, it breaks the pusher motor circuit and movement of the pusher ceases. In order to restart the pusher and also reverse the carriage when it attains the end of its travel, I have provided a combination switch at each end of the apparatus. These switches are designated as switches 197. They each embody a pair of contact arms 198 and 199 and a common operating rod 201 carrying a finger 202 at the end thereof. Contact 198 controls the circuit of pusher motor 154, while contact 199 controls the reversing circuit of carriage motor 56.

Cooperating with switches 197 are a pair of cams 203 which are carried by any suitable part of the carriage; and accordingly, when carriage C reaches one end of its travel one of the cams 203 will strike one of the switch rods 201 so as to close the pusher motor circuit and also reverse the circuit for carriage motor 56. When the pusher has advanced one step, one of the cam faces 194 will actuate switch 193 to again stop the pusher motor as previously described. The motors 56 and 154 are preferably provided with magnetic brakes so that they will promptly come to rest when their circuits are broken.

When the pusher has attained the end of its travel, it is automatically stopped and reversed by means of a switch 204 having an operating

rod 205 which cooperates with a cam 206 on member 186.

In order to provide for the automatic transition from a slow carriage speed to a fast carriage speed or vice versa, I have provided intermediate switches 208 which are operable to change the motor connections to secure the desired speed. Each switch 208 is provided with an operating plunger 209 which cooperates with cam 203 whereby during a predetermined stage of carriage movement one of the switches 208 will be thrown to reduce or increase the speed of carriage motor 56, and thereby vary the carriage speed automatically. Switches 208 are preferably mounted for adjustment longitudinally of the carriage path, in order that the point or points at which a change in the carriage speed will occur can be adjustably varied to suit the particular type of work operated upon. Also, if desired, additional switches similar to switches 208 may be interposed in the path of carriage travel for introducing more than two speed changes for each stroke of the carriage.

For instance, if the work piece must be intensively cleaned adjacent the ends thereof, the switches are so adjusted that the carriage will initially undergo a slow movement; one of the cams 203 will then strike one of the switches 208 to cause motor 56 to accelerate, cause the carriage to undergo a more rapid intermediate stage of movement; the other cam 203 will then strike the other switch 208 so as to again restore the slow speed of carriage movement so as to cause the blast streams to intensively clean the other end of the work piece operated upon. If desired, the switches may be adjusted to produce the opposite effect; namely, to cause the carriage to move fast over the ends of the work and to undergo a slower movement intermediate the ends of the work so as to subject the mid-portion of the work to an intensive cleaning action.

As previously indicated, the circuit for the wheel motors 49 is preferably independent of the other circuit so that they may be started by push buttons and be operated continuously except when the machine is shut down.

The form of operation of carriage C and pusher G will vary depending upon the nature of the work handled by the machine. For instance, if the work requires a fairly uniform cleaning action over its entire surface, the pusher will be operated to advance the work one step each time the carriage reaches the end of its travel. As previously pointed out, if the work possesses "dirty spots" or areas requiring a more intensive blasting action switches 208 are so adjusted as to cause the carriage to travel slower in those regions and thereby allow the blast streams to act for a longer time upon those areas.

If desired, additional wheels may be mounted upon carriage C and be disposed at various inclinations to meet the particular working condition involved.

I have shown and prefer to employ a conveyor that assumes the form of a table, because it possesses two zones—permitting one to be loaded while the other is in the blast cabinet—but it is to be understood that if desired other forms of conveyors may be used without departing from the spirit of my invention.

The invention may be embodied in other specific forms without departing from the spirit or essential characteristics thereof. The present embodiment is therefore to be considered in all respects as illustrative and not restrictive, the

scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In an abrading apparatus, a work support upon which articles of work may rest, a carriage mounted for transverse movement above said work support, a pair of rotatable abrasive propelling mechanisms mounted on said carriage and operable to discharge abrasive downwardly upon said work, said mechanisms each embodying a rotor mounted for rotation about an axis inclined with respect to the plane of movement of said carriage and operable to discharge a blast stream of abrasive downwardly upon said work, said rotor axes being disposed at opposite inclinations with respect to said plane of movement of said carriage for directing said abrasive blast streams against the ends as well as the upper surfaces of said work, and means for moving said carriage for causing said blast streams to traverse said work.

2. The abrading apparatus described in claim 1, wherein said rotor axes are so inclined as to cause said abrasive blast streams to converge but are so directed as to strike the work before they become sufficiently proximate to each other to intermingle.

3. The abrading apparatus described in claim 1, wherein said rotor axes are disposed in vertical parallel planes which extend in the direction of movement of said carriage.

4. In an abrading apparatus, a work support upon which articles of work may rest, a carriage disposed above said work support and mounted for movement in a substantially horizontal plane, at least one blasting mechanism mounted on said carriage and operable to project an abrasive blast stream downwardly upon an article of work supported on said work-support, means for causing said carriage to make at least one pass over said work, and pusher means for causing said article to move a predetermined distance in a direction substantially normal to the direction of movement of said carriage, and means for causing said carriage to make another pass over said work.

5. The abrading apparatus described in claim 4, wherein said pusher means embodies means for variably adjusting the distance through which it moves, for varying the abrading action upon the work.

6. The abrading apparatus described in claim 4, wherein said pusher means embodies an electric motor, and control means are provided for automatically energizing said motor when said carriage reaches one end of its movement.

7. The abrading apparatus described in claim 4, wherein said pusher means embodies control means coordinated with said carriage for automatically causing said pusher to successively advance said work each time said carriage attains one end of its movement.

8. In an abrading apparatus, a housing providing a blasting zone, a conveyor providing an upwardly facing surface upon which articles of work may be placed, said conveyor being movable to bring articles of work into and out of said blasting zone, a carriage mounted for movement in a substantially horizontal plane above said conveyor and having means for directing a blast stream

down upon articles of work supported on said conveyor, pusher means for periodically moving said work in a direction substantially normal to the direction of movement of said carriage to expose different areas thereof to the action of said blast stream as said carriage moves from one end of its travel to the other, and control means for preventing said pusher means from operating until said conveyor is disposed in a predetermined blasting position.

9. The abrading apparatus described in claim 8, wherein control means are also provided for preventing said conveyor from operating until said pusher means is disposed in retracted condition.

10. The abrading apparatus described in claim 8, wherein said pusher means comprises a bar element mounted for reciprocation into and out of said blasting zone in a direction substantially normal to the path of movement of said carriage and is operable to directly engage said work.

11. The abrading apparatus described in claim 8, wherein said conveyor comprises a table mounted for rotation about a substantially vertical axis.

12. In an abrading apparatus, a carriage mounted for reciprocation in a substantially horizontal path, at least one abrasive propelling rotor mounted for rotation on said carriage, a motor mounted on said carriage and connected to said rotor, an abrasive conveying mechanism for supplying said rotor with abrasive, and a second motor mounted on said carriage and drivingly connected to said conveyor.

13. The abrading apparatus described in claim 12, wherein a hopper is also mounted on said carriage, the lower end of said hopper communicating with said conveyor and the upper end of said hopper providing an upwardly facing-opening which is elongated in the direction of travel of said carriage, thereby adapting it to be fed from a stationarily supported abrasive feed conduit.

14. The abrading apparatus described in claim 12, wherein said first and second motors are engaged by a common electrical circuit, whereby, when said rotor is stopped said conveyor will automatically cease feeding abrasive thereto.

15. The abrading apparatus described in claim 12, wherein said conveyor is supplied with abrasive through a solenoid controlled valve, and said first and second motors and said valve are energized by a common electrical circuit, whereby, when said circuit is broken to stop said rotor, the flow of abrasive is automatically stopped.

16. In an abrading machine, a work support upon which articles of work may rest, a carriage mounted for reciprocatory movement above said work support, at least one abrasive propelling wheel mounted on said carriage and having a prime mover for driving it mounted on said carriage, and means for reciprocating said carriage for causing said abrasive propelling wheel to direct a stream of abrasive upon said work, throughout the length of said work, said means for reciprocating said carriage embodying automatically operable control means for causing said carriage to travel at a slower speed during at least one portion of its stroke, for causing said work to be subjected to a greater abrading action over part of its length.

17. In an abrading machine, a work support upon which articles of work may rest, a carriage mounted for reciprocatory movement above said work support, at least one abrasive propelling wheel mounted on said carriage and having a prime mover for driving it mounted on said car-

riage, and means for reciprocating said carriage for causing said abrasive propelling wheel to direct a stream of abrasive upon said work, throughout the length of said work, said abrasive propelling wheel being operable to discharge abrasive substantially solely downwardly in a plane disposed normal to the axis of rotation of

said wheel, said wheel being mounted on said carriage with its axis inclined to the plane of travel of said carriage, whereby said discharge therefrom is so inclined as to abrade the ends as well as the upper surfaces of the article of work.
